UNITED STATES PATENT AND TRADEMARK OFFICE
CERTIFICATE OF CORRECTION

PATENT NO. : D1,044,832 S
APPLICATION NO. : 29/838029
DATED : October 1, 2024
INVENTOR(S) : Min Liu, Teofila Connor and David Muro

It is certified that error appears in the above-identified patent and that said Letters Patent is hereby corrected as shown below:

On the Title Page

Column 1, item (72):

“(72) Inventors: Min Liu, San Francisco, CA (US)
Teo Connor, San Francisco, CA (US)
David Muro, San Francisco, CA (US)”

Should read:

--(72) Inventors: Min Liu, San Francisco, CA (US)
Teofila Connor, San Francisco, CA (US)
David Muro, San Francisco, CA (US)--

Signed and Sealed this
Twenty-first Day of October, 2025

John A. Squires
Director of the United States Patent and Trademark Office
